CLAIM

The ornamental design for an audio cable connector as shown and described.

DESCRIPTION

FIG. 1 is a perspective view of an audio cable connector; FIG. 2 is a right side view of the audio cable connector of FIG. 1;

FIG. 3 is a left side view of the audio cable connector of FIG. 1;

FIG. 4 is a bottom view of the audio cable connector of FIG. 1;

FIG. 5 is a top view of the audio cable connector of FIG. 1; FIG. 6 is an enlarged front view of the audio cable connector of FIG. 1; and,

FIG. 7 is an enlarged rear view of the audio cable connector of FIG. 1.

The subject matter delineated with broken lines illustrates environment and is not part of the claimed design.

1 Claim, 4 Drawing Sheets(56)
